13 Claims. (Cl. 19—1)

This invention relates to improvements in or relating to the collection, treatment and disposal of staple fiber produced by cutting continuous filaments.

According to the present invention, the staple fiber is removed from the point at which it has been cut from the continuous filaments by means of suction applied in such a way as to discharge the fibers below the level of a liquid. The fiber is thus collected in the liquid as a compact mass, and is nevertheless arranged in the mass in more "open" condition as regards the spacing of fiber from fiber, the action of the liquid serving to break up close agglomeration of fibers. This opening action may be assisted by agitation of the fibers while they are still in the liquid, e. g. by having a flowing body of liquid. The liquid, moreover, may be used to apply any desired treatment for modifying the properties of the fibers, for example the application of an identifying tint or a content of anti-static finish in the case of fibers prone to electrification, or the saponification of cellulose ester filaments, e. g. cellulose acetate filaments. The invention thus enables the ready collection in compact form of fibers ready, after a suitable drying operation, for the subsequent spinning process for which they are intended.

The fibers may be cut wet or dry. In the case of cutting continuous filaments in dry condition, the suction may serve to maintain the feeding of the continuous filaments into the cutting machine, in addition to removing the fibers from the delivery side of the machine.

In its simplest form, the apparatus for carrying out the invention comprises a cutting machine, a suction conduit leading from the cutting machine down into an enclosed chamber adapted to contain liquid to a level above the end of the conduit, and means to apply suction to the chamber above the liquid level. The amount of applied suction is sufficient to draw entraining air from the delivery conduit into the mass of the liquid, the entrained fibers remaining in the liquid. In order, however, to prevent clogging of the outlet of the delivery conduit, means should be provided to carry the fibers away from this point, these means preferably operating in a continuous manner. For example, the liquid may be made to flow past the outlet of the conduit so as to carry the wetted fibers with it. For this purpose, the whole body of liquid may move or local movement may be set up, as by the use of a jet of air or liquid. The fibers may be

- allowed to collect to any suitable amount in the chamber, and then removed as a mass. For this purpose, two chambers may be provided for alternative use, changeover valve mechanism enabling the delivery conduit and the suction to be switched from one chamber to another. Suction of some 4 to 5 inches water gauge may be used and this suction may serve to hold a removable cover resting by gravity on the chamber, a suitable rubber or other gasket being provided to seal the cover. The cover and/or the walls of the chamber may be provided with a window to enable the amount of fiber at any time in the trough to be readily seen.
- 15 Provision may be made for continuous removal of the fiber from the body of liquid in which it is collected, as by providing a continuous current of liquid, and removing liquid and fiber together, afterwards separating as much free liquid as possible from the fiber.
- The invention will now be described in greater detail with reference to the accompanying drawings which show diagrammatically and partly in section various forms of apparatus.
- 20 Fig. 1 shows a simple apparatus comprising a chamber from which the fiber must be discharged at intervals;
- Fig. 2 shows a detail of the modification suitable for apparatus of the type shown in Fig. 1;
- 30 Fig. 3 shows apparatus arranged for the continuous discharge of fiber by means of a belt;
- Fig. 4 and 5 show two forms of apparatus providing for discharge and draining of the fiber;
- 35 Fig. 6 shows apparatus for a modified form of belt discharging device operating in conjunction with apparatus for the further treatment of the fiber; and
- 40 Fig. 7 shows a modified form of apparatus also including a preliminary suction chamber.
- Referring to Fig. 1, a bundle 1 of continuous filaments passes through a pair of nip rollers 2 and a funnel 3 to a cutting device comprising a cutting cylinder 5 and a fixed blade 6. The cutting machine 4 is enclosed by a member forming a conduit 8 discharging downwardly into a chamber 9 containing liquid 10 to a height above the mouth of the conduit 8. Suction applied by a pump 11 through a pipe 12 above the level of the liquid 10 sucks the fibers cut by the machine 4 through the conduit 8 as well as assisting in the feeding of the end of the bundle 1 through the funnel 3. As the fibers leave the conduit 8 they are forced to pass into the

liquid 10 and thus become thoroughly wetted. The fiber bundles are also broken up by the action of the liquid and the mass of bundles produced is thus brought into a better condition for the subsequent spinning of the fibers after the mass has been dried. A cover 13 with handles 14 permits removal of the fibers from the chamber 9 when a sufficient quantity has collected. The weight of the cover together with the suction within the chamber enables the cover to seal itself against the top of the chamber.

Continuous collection may be provided by means of two chambers 9 as indicated in Fig. 2. The conduit 8 may be put into communication with either of the chambers by means of a valve 15 controlled by a counter-weighted lever 16. With this arrangement emptying of one chamber 9 may proceed while the other is being filled.

In order to prevent clogging of the mouth of the conduit 8, the basic apparatus shown in Fig. 1 may be developed into one or other of the forms shown in Figs. 3-7. For example, in Fig. 3 the discharge conduit 8 leads the fibers into a chamber 19 without a bottom, the sides 20 of the chamber extending below the level of liquid 21 contained in a trough 22 so as to keep the chamber 19 sealed when suction is applied to the pipe 23. An endless band 24 passing below the chamber 19 receives the mass of fiber as it collects and carries it to the right. The band then raises the fiber to nip rolls 25 which remove surplus liquid and deliver the fiber for discharge as the band passes round the roller 26. Doctor blades 27 prevent clinging of the fiber to the upper roller 25 and assist in removing the fiber from the band 24.

In Fig. 4 the conduit 8 discharges below the level of liquid 28 in a funnel-like chamber 29 to which suction is applied through the conduit 129. Liquid is fed to the chamber by means of a pipe 30 and is permitted by a valve 31 to escape through the stem 32 of the chamber at a rate that maintains the mouth of the conduit 8 below the level of the liquid. As fiber collects in the chamber 29 it escapes by the stem 32 through nip rolls 33 and is discharged on to a draining belt 34. Doctor blades 35 prevent clinging of fiber to the rollers 33. A further doctor blade 36 assists in discharging of the fiber from the belt 34. Liquid expressed from the fiber by the rolls 33 and draining from the belt 34 is caught in a trough 37 together with any overflow liquid from the chamber 29 which escapes by the pipe 38. The liquid is returned from the trough 37 to the pipe 30 by the pump 39. An inspection window 40 permits the amount of fiber collecting inside the tank to be seen.

In Fig. 5 a conduit 8 is used in connection with a chamber 29 of the kind shown in Fig. 4, suction being applied through the conduit 129. Discharge from the chamber is effected through a bent stem 41 which delivers the wet mass of fibers on to a screen 42 in a trough 43, the flow of liquid carrying the fibers away from the discharge point. The drained fibers can be lifted by hand or otherwise from the screen 42, the water collecting in the trough 43 being returned by the pump 39 to the chamber 29.

In Fig. 6 the chamber 44 to which suction is applied through the conduit 144 and the trough 45 serve for the collection of fiber from the conduit 8 in much the same way as the apparatus shown in Fig. 3. The liquid 46 is, however, moved from left to right in the trough 45 by means of a pump 47 and return pipe 48 so that fibers are 75

carried under the depending wall 49 to an endless band 50, which lifts them from the trough 45, surplus liquid being expressed by means of the rolls 51. The flow of liquid in the trough 45 assists in opening the fibers. The mass of fiber is discharged over one of the doctor blades 52 into a trough 53 containing a rake 54 lifted and reciprocated in any suitable way so as to open up the fibers and at the same time carry them towards and up the discharge slope 154 for passage through nip rolls 55 from which they are discharged into a suitable receptacle such as the truck 56.

In Fig. 7 is shown an apparatus particularly suitable for dealing with dry-cut fibers. The discharge conduit 8 leads into a suction chamber 57 extending transversely away from the conduit. The larger cross-section of the chamber as compared with that of the conduit reduces the velocity of the fibers and the fibers progress to the right-hand end of the chamber with a swirling motion that serves to open the fibers. The fibers are sucked down the discharge conduit 58 into a liquid chamber 59 having a depending wall 60 forming a seal between the chamber and a trough-like extension 61. Suction is applied to the chamber 59 through the conduit 159. The liquid 62 is drawn from the chamber 59 into the trough 61 by means of the pump 63 and return pipe 64, the motion of the liquid carrying the fibers from the chamber 59 and causing them to collect against a screen 65 ready for removal.

The liquid into which the fibers are discharged may contain an anti-static finish in such concentration that when surplus liquid is expressed from the fibers and the fibers are dried, the desired amount of finish is left on the fibers.

The bath of liquid is replenished to make up the quantity removed with the fibers. For example, in the case of the apparatus shown in Figs. 1 and 2, replenishment may take place each time a bath is cleared of fibers; in the case of the other forms of apparatus, replenishment may conveniently be continuous into the part of the liquid chamber open to the atmosphere.

Having described our invention, what we desire to secure by Letters Patent is:

1. Method of cutting and collecting staple fiber, comprising cutting staple fiber from continuous filaments, guiding the fibers from the cutting point below the level of a liquid and applying sub-atmospheric pressure to the surface of said liquid so as to discharge said fibers into said liquid below said surface.

2. Method of cutting and collecting staple fiber, comprising cutting staple fiber from continuous filaments, guiding the fibers from the cutting point below the level of a liquid, agitating the fibers while they are in the liquid and applying sub-atmospheric pressure to the surface of said liquid so as to discharge said fibers into said liquid below said surface.

3. Method of cutting and collecting staple fiber, comprising cutting staple fiber from continuous filaments, guiding the fibers from the cutting point below the level of a flowing body of liquid and applying sub-atmospheric pressure to the surface of said liquid so as to discharge said fibers into said liquid below said surface.

4. Method of cutting and collecting staple fiber, comprising cutting staple fiber from continuous filaments, guiding the fibers from the cutting point below the level of a liquid, continuously removing the fibers from the liquid and applying sub-atmospheric pressure to the surface of said

liquid so as to discharge said fibers into said liquid below said surface.

5. Method of cutting and collecting staple fiber, comprising cutting staple fiber from continuous filaments in dry condition, removing the fibers by suction from the cutting point to a space in which the velocity of the fibers is reduced, guiding the fibers from said space below the level of a body of liquid and applying sub-atmospheric pressure to the surface of said liquid, so as to discharge said fibers into said liquid below said surface.

6. Method of cutting and collecting staple fiber, comprising cutting staple fiber from continuous filaments, guiding the fibers from the cutting point below the level of a liquid containing an anti-static finish and applying sub-atmospheric pressure to the surface of said liquid so as to discharge said fibers into said liquid below said surface.

7. Method of cutting and collecting staple fiber, comprising cutting staple fiber from continuous filaments having a cellulose ester basis, guiding the fibers from the cutting point below the level of a liquid adapted to saponify the fibers and applying sub-atmospheric pressure to the surface of said liquid so as to discharge said fibers into said liquid below said surface.

8. Apparatus for cutting and collecting staple fiber, comprising a cutting machine, a suction conduit leading from the cutting machine, an enclosed chamber into which the conduit projects downwardly, the chamber being adapted to contain liquid to a level above the end of the conduit, and means to apply suction to the chamber above the liquid level.

9. Apparatus for cutting and collecting staple fiber, comprising a cutting machine, a suction conduit leading from the cutting machine, an

5 enclosed chamber into which the conduit projects downwardly, the chamber being adapted to contain liquid to a level above the end of the conduit, means to apply suction to the chamber above the liquid level and means for agitating the fibers in the liquid chamber.

10. Apparatus for cutting and collecting staple fiber, comprising a cutting machine, a suction conduit leading from the cutting machine, an enclosed chamber into which the conduit projects downwardly, the chamber being adapted to contain liquid to a level above the end of the conduit, means to apply suction to the chamber above the liquid level and means for producing a flow of liquid through the chamber.

15 11. Apparatus for cutting and collecting staple fiber, comprising a cutting machine, a suction conduit leading from the cutting machine, an enclosed chamber into which the conduit projects downwardly, the chamber being adapted to contain liquid to a level above the end of the conduit, means to apply suction to the chamber above the liquid level and means for conveying the fibers from the chamber.

20 12. Apparatus for cutting and collecting staple fiber, comprising a cutting machine, a suction conduit leading from the cutting machine, said conduit including a suction chamber, a further enclosed chamber into which the conduit projects downwardly, the further chamber being adapted to contain liquid to a level above the end of the conduit, and means to apply suction to the further chamber above the liquid level.

25 13. Apparatus according to claim 12, wherein the suction chamber extends in a transverse direction with respect to the remainder of the conduit in which it is included.
